(57) **CLAIM**

The ornamental design for a vehicle control panel, as shown and described.

DESCRIPTION

FIG. 1 is a perspective view of a vehicle control panel showing my new design; and,

FIG. 2 is an elevational view thereof.

The broken line showings of the indicia and circles and rectangles in the central rectangular area and the boundary of the claim itself are for illustrative purposes and form no part of the claimed design.

1 Claim, 1 Drawing Sheet

FIG. 2

FIG. 1
